UNITED STATES PATENT OFFICE.

RICHARD LOGAN, OF LISBON, NEW YORK.

SWING-STANCHION.

No. 927,562.

Specification of Letters Patent.

Patented July 13, 1909.

Application filed November 6, 1908. Serial No. 461,433.

To all whom it may concern:

Be it known that I, RICHARD LOGAN, a citizen of the United States, residing at Lisbon, in the county of St. Lawrence and State of New York, have invented certain new and useful Improvements in Swing-Stanchions, of which the following is a specification.

This invention relates to care of live stock and has especial reference to a novel formation of stanchion to be employed for securing cattle within their stalls.

An object of this invention is to construct a stanchion which is adapted for pivotal movement in order to form a device of this character which will be as comfortable as is consistent with the nature thereof.

The invention has for another aim the provision of a stanchion with means whereby the same will be locked or released from a distance rearwardly of the same, thereby producing a device which is applicable to congested conditions.

The invention further aims the provision of a stanchion, the arms of which are provided with means whereby the same are retained from rotation when in an open position for the reception of the head of the cattle therebetween.

For a full understanding of the invention reference is to be had to the following description and accompanying drawings, in which:—

Figure 1 is a front elevation of the complete device in an open position. Fig. 2 is a view of the same showing the same as closed. Fig. 3 is a rear elevation of the stanchion showing the bars in an open position. Fig. 4 is a section on the line 4—4 of Fig. 3. Fig. 5 is a transverse section of the device on the line 5—5 of Fig. 3.

Corresponding and like parts are referred to in the following description and indicated in all the views of the drawings by the same reference characters.

Referring to the drawings, the numeral 10 designates a rectangular framework which is vertically disposed and which is provided with a raised base 11 intermediate of the lower portion thereof. A cross-arm 12 is pivotally mounted upon the base 11 by means of a bolt 13 which is secured vertically therethrough and which is extended through the base 11 into the lower portion of the framework 10. A washer 14 is rigidly positioned about the bolt 13, the

bolt 13 being rigidly secured to the cross-arm 12, and is secured at one side to the inner extremity of a spring 15 which is carried by the base 11 and which exerts a tension upon the washer 14 to normally retain the cross-arm 12 in the plane of the framework 10. The opposite extremities of the cross-arm 12 are forked in which are pivotally secured the lower extremities of bars 16 and 16' which extend upwardly therefrom and are engaged at their upper extremities against abutments 17 which are depended from the upper portion of the framework 10. The abutments 17 are recessed in their inner opposite faces for engagement with beveled portions formed upon the upper extremities of the bars 16 and 16' to prevent the lateral displacement of the bars 16 and 16' when pressure is exerted against the same. Swivelly mounted upon a king-bolt 18 is a head 19 which is depended centrally upon the upper portion of the framework 10 intermediate of the upper extremities of the bars 16 and 16' which are provided at their lower ends with beams 20 and 21 which are disposed in parallel and extend longitudinally within the frame 10. The beams 20 and 21 are provided between their outer opposite extremities with arms 22 and 23 which depend therefrom and carry idlers 24 and 25 over which is passed an endless belt 26. The endless belt 26 is rigidly secured at its opposite portions to the bars 16 and 16' for the purpose of insuring a uniform movement of the same relative to one another when operated. The bar 16' is provided adjacent its upper extremity with an eye-bolt 27 which carries the inner extremity of a spring 28 disposed upon an ear 29 which is upwardly extended from the outer adjacent end of the cross-beams 20 and 21. The head 19 is provided upon its outer face with a pulley 30 which is adapted for the reception of a cable 31 which is secured at its lower extremity in the eye-bolt 27 and which extends upwardly from the head 19 where it is engaged over a series of pulleys 32 and depended at a convenient point where it is provided with a handle 33 for engagement by the operator. The opposite side of the head 19 is provided with an L-plate 34 which is hingedly disposed between lugs 35 outwardly extended from the head 19, the flanged portion of the plate 34 being extended outwardly and engaged with the lower extremity of a cable

36 which is passed upwardly therefrom through a guide 37 where it is engaged over a series of pulleys 38 to a position adjacent the cable 31 where it is provided with a handle 39. The plate 34 is provided with latches 40 and 41 which are oppositely disposed therefrom and adjustably secured thereto by means of the formation of a plurality of apertures longitudinally disposed 5 in the same through which detachable pins 10 42 are secured and which are supported in such relation by means of slotted flanges 43 which are turned outwardly and vertically from the head 19. The plate 34 is adapted 15 to be tensionally retained against the face of the head 19 by means of coil springs 44 which are positioned loosely in enlarged apertures formed through the head 19 and are secured at their opposite extremities to 20 the inner face of the plate 34 and to a transverse pin 45 positioned against the opposite face of the head 19. The latches 40 and 41 are each provided with inwardly beveled extremities which are adapted for 25 sliding movement over beveled faces of the bars 16 and 16' for the purpose of admitting of the automatic action of the latches 40 and 41.

The operation of the device is as follows:—Normally the bars 16 and 16' are converged and engaged against the inner recessed faces of the abutments 17. The stanchion is adapted to be mounted at the end of a stall and the cattle which is to be secured therein is driven into the stall and is adapted to engage its head between the bars 16 and 16' when the operator grasps the handle 33 to draw upon the cable 31 to swing the bar 16' inwardly. This action 30 causes the movement of the endless belt 26 as the same is secured to the bar 16' and thus causes the inward movement of the bar 16 owing to the rigid connection between the same and the belt 26. As the bars 16 and 40 16' are drawn inwardly the same engage against the outer extremities of the latches 40 and 41 and ride over the beveled ends formed thereon to swing the plate 34 outwardly and to admit of the passage of the 45 bars 16 and 16' inwardly of the shoulders of the latches 40 and 41. When the bars 16 and 16' are closed the shoulders of the latches 40 and 41 are engaged with the bars and are pressed outwardly of the same when 50 they are admitted to swing inwardly by the action of the springs 44 on the plate 34 to prevent the divergence of the bars 16 and 16' and to thus secure the same in a locked position. 55

60 When it is desired to release the cattle from the bars 16 and 16' the opposite handle 39 is grasped and drawn downwardly which causes the raising of the flanged portion of the plate 34 through the medium of the cable 65 36 to swing the latches 40 and 41 outwardly

thereby admitting of the release of the bars 16 and 16'.

It is readily understood from the foregoing that when the bars 16 and 16' are converged the same, together with the head 70 19, are permitted a rotary motion about the bolts 13 and 18 and admit of the side motions of the cattle which are secured therein. The spring 15 is employed for the purpose of holding the bars 16 and 16' in the plane 75 of the frame 10 when the device is in an inoperative position in order to maintain the same in such position that it needs no adjustment to drive a herd of cattle therein.

Having thus described the invention what 80 is claimed as new is:—

1. A device as specified comprising a frame, a base positioned in said frame, cross-arms pivotally mounted on said base, bars pivotally carried at the outer extremities of 85 said cross-arms and upwardly extended therefrom, a head pivotally disposed in said frame, a plate hingedly carried on one side of said head, latches mounted on said plate for engagement with said bars when the 90 same are converged, a cable carried by said plate for swinging the same outwardly to disengage said latches from said bars, and a second cable carried by said head and connected to said bars for contracting the same. 95

2. A device as specified comprising a frame, a pair of bars hingedly disposed in said frame and upwardly extended therein, a head carried by said frame intermediately of said bars, beams carried by said head and extended longitudinally therefrom, idlers positioned in the ends of said beams, an endless belt engaged over said idlers, said endless belt being secured to said bars, a cable carried by said head and engaged with one 100 of said bars to operate both of said bars, latches carried by said head for engagement with said bars at times and a cable connected to said latches for releasing said bars. 105

3. A device as specified comprising a 110 frame, a pair of bars pivotally and rotatably mounted in said frame, means disposed between said bars for communicating opposite motion to the same, a cable carried by one of said bars for drawing the same inwardly, 115 a head carried by said frame between the upper extremities of said bars, latches mounted on said head for engagement with said bars at times and a cable connected to said latches for releasing the same from said bars. 120

4. A stanchion as specified comprising a frame, bars pivotally positioned in said frame and extended upwardly therein, a head carried by said frame between the upper ends of said bars, latches carried by said head for engagement with said bars when the same are converged, a plate hingedly disposed on said head and connected to said latches, a spring supported by said head and 125 130

engaged with said plate for normally retaining said plate against said head, a cable carried by said plate for swinging the same outwardly at times, means carried by said head and connected to said bars for communicating motion between the same, a spring carried by said head and engaged with one of said bars for normally holding

the same in an outward position and a cable carried by said head and engaged with one 10 of said bars for drawing the same inwardly at times.
